SELVEDGE PRINTING APPARATUS FOR WOVEN GOODS

Hans Nabholz, Zurich, Switzerland, assignor to
Maschinenfabrik Rüti vormals Caspar Honegger, Rüti, Switzerland

Application February 10, 1936, Serial No. 63,230

1 Claim. (Cl. 101—248)

Machines for printing trade marks or other indications on the selvedges of cloth are already known; in such machines the cloth, which is always slightly varying in width, is guided by a special appliance generally actuated by compressed air or by electricity, in such a way that the stamp is put on the selvedge always at exactly the same distance from the cloth-border.

In the apparatus according to the present invention it is not the cloth selvedge which is guided under the stamp, but the stamp is displaced or steered and follows the track of the selvedge.

Further for getting exact prints it is necessary, that all the letters of the stamp are covered with an even film of the ink; therefore it is necessary that the roller which applies the ink to the stamp turn with the same circumferential speed as the stamp and does so, before the stamp comes into contact with the roller. If the speed of the roller were less than the speed of the stamp then the first letter of the mark would get too much ink and produce an uneven print.

In the present invention a selvedge-printing apparatus is shown, in which the stamp is steered to follow exactly the selvedge-track and which is provided with a special appliance for laying a thin film of ink on the stamp by means of a roller, rotating with the same circumferential speed as the stamp.

30 The annexed drawing shows diagrammatically an embodiment of the invention:

Fig. 1 is a side view of the selvedge printing apparatus, fixed to a Palmer cloth finishing machine;

35 Fig. 2 shows the shaft-end of the stamp-bearer and the parts for displacing the latter on the shaft;

Fig. 3 shows the ink-box and the ink rollers, and as well as the stamp-bearer;

40 Fig. 4 shows some details of the stamp-bearer.

In order to show the working of the selvedge-printing apparatus, the latter is represented in Fig. 1 applied to a felt-cloth calender, a so-called Palmer, for finishing woven fabrics. 1 is the frame of such a Palmer, 2 is a heated cylinder, 3 a guiding cylinder for the felt-cloth 4, and 5, 6, 7, 8, 9, 10, 11 and 12 are guiding rollers for the felt cloth. The fabric 11 runs through the Palmer between the heated cylinder 2 and the felt cloth 4, and is conducted over the guiding rollers 13, 14, 15, 16 and on its way one selvedge is marked by the stamp of the selvedge-printing apparatus, mounted on the supports 18, which are fixed to the Palmer.

55 These supports 18 carry a shaft 19, on which is

placed the carrier 20 of the stamp plate 21, movable to the right and to the left by means of a key and a groove. The shaft 19 is driven from the guiding roller 7 by a chain by means of the chain wheels 22a and 22b and by the spur gear wheels 23 and 24.

The boss of the stamp-bearer 20 has a groove 25, in which the end 26 of the spindle 27 enters, the latter being guided in a box 28 in the support 18 by means of a key fixed to the box 28 and a groove along the spindle 27. The spindle 27 has a threaded surface and a chain wheel 33 with a corresponding threaded bore mounted thereon. Said wheel 33 is secured by its flange 34 to the support 18. Thus the wheel 33 when actuated 15 causes the spindle 27 to slide inwardly or outwardly in its bearing and adjusts the stamp carrier 20.

A pin 35a on the rod 35 which is placed at an adequate distance of the roller 14 and which is fixed to the spindle 27, indicates whether the cloth-selvedge runs straight or whether its track deviates to the right or to the left. When such a deviation takes place, then the chain wheel 33 is turned by the attendant of the machine by means of the handwheel 30 on the steering post 29, whereby the chain wheel 32 and the chain also are turned so that the spindle 27 is made to slide along the key fixed to the box 28, carrying with it the stamp-carrier 20. The chain wheel 33 is turned so long, until the track of the cloth selvedge coincides again with the pin 35a. The distance between the pin 35a and the roller 14 is such that the time wanted for the cloth to run through this distance, is just sufficient for removing the spindle 27 so much that when the part of the cloth which was deviating from the straight track arrives on the roller 14, then its border runs at an unchanged distance of the stamp track.

The stamp-ink is poured in the box 36 and is taken from there by a system of rollers 37, 38, 39, 40, 41, driven from the shaft 19 by means of the chain-wheels 42 and 43, the small shaft 44 and the toothed spur-wheels 45—46. These rollers 37—41 grind well the ink and transform it into a thin film, which is applied evenly on a swinging roller 47, which by means of the cam 48, the double lever 49 and the connecting rod 50 is oscillated about the pin 51. The cam 48 is so formed that the swinging roller 47 is brought to a point in the track of the stamp before the stamp arrives at that point. To the bearer 20 on the side of the stamp 21 is screwed a segment-like piece 52, the track of which has exactly the 55

same diameter as the track of the stamp; this piece 52 rotates the roller 47 before the stamp touches it, whereby the circumferential speed of the roller 51 and of the stamp 20 will be exactly the same and the ink-film is evenly transferred onto the stamp.

The printing by the stamp on the cloth-selvedge takes place at the moment when the cloth runs over the roller 14, covered with rubber and supported by the bearing levers 53 on the shaft 54; by means of the handwheel 56, with spindle 57 and the lever 55 the roller 54 is put into the right position according to the thickness of the fabric.

Obviously the present invention is not limited to the features specifically mentioned above and it must be understood that various constructional modifications may be adopted within the scope of the said invention, and that it might be applied

not only to a Palmer, but to any kind of machine through which cloth is conducted.

What I claim is:

In an apparatus for printing trade-marks or other indications on the selvedge of woven cloth-pieces, without the cloth borders being forcibly guided, the combination with a member enabling the attendant to ascertain the deviation of the cloth border from a straight line at an adequate distance from the place in the printing apparatus where the stamping takes place, of means enabling the attendant to laterally adjust the stamp bearer according to the said deviation before the deviating part of the cloth has reached the said place for the purpose of obtaining prints on the laterally adjusted cloth border always in the same distance from this border.

HANS NABHOLZ.
